(57) **CLAIM**

We claim, the ornamental design for a motor vehicle roof component, as shown and described.

DESCRIPTION

FIG. 1 is a bottom plan view of a motor vehicle roof component, showing our new design in a condition of use; FIG. 2 is a bottom, front, right side perspective view thereof; FIG. 3 is a bottom plan view thereof; FIG. 4 is a left side view thereof, the right side view being a mirror image; and, FIG. 5 is a bottom, front, right side perspective view thereof, shown in a condition of use. The broken lines illustrate environmental structure which forms no part of the claimed design.
